UNITED STATES PATENT OFFICE.

ROBERT CLARK, JR., OF NEWARK, NEW JERSEY, ASSIGNOR TO YATES,
WHARTON & CO., OF SAME PLACE.

HAT-FLANGING MACHINE.

SPECIFICATION forming part of Letters Patent No. 228,606, dated June 8, 1880.

Application filed March 22, 1880. (No model.)

To all whom it may concern:

Be it known that I, ROBERT CLARK, Jr., of Newark, in the county of Essex and State of New Jersey, have invented a new and useful 5 Improvement in Hat-Flanging Apparatus, of which the following is a specification.

My invention relates to an improvement in hat-flanging apparatus; and it consists, first, in the combination, with a sand-bag and treadle 10 for lifting the same, of a crane or derrick for transferring the bag from the hot-table to the flange; and, second, in the combination of a series of such cranes with the wall or ceiling of a building, and with continuous work-benches and hot-tables beneath the cranes. 15

Such a method of mounting the transferring devices dispenses with the use of distinct machines for the purpose named by utilizing the walls and benches of the hat-shop 20 for the support of the operative mechanism, while the substitution of a crane for the various machines previously devised for moving the sand-bag to and fro greatly diminishes the cost of the attachments required for each 25 bag and the space they occupy in the workshop.

In the drawings annexed, Figure 1 represents a section of a work-bench and hot-table provided with my hat-flanging apparatus secured to the wall and ceiling of the workshop. 30 Fig. 2 is a plan of the same, showing how several sand-bags may be operated side by side in much less space than the same number of machines could be mounted.

A is the side wall of a workshop; B, the floor; C, the ceiling, and D the work-bench, set out from the wall a convenient distance to introduce the hot-table E.

S is the sand-bag, and T the crane, having 40 a pulley or roller, a, provided upon its axle of rotation f, and a cord, b, attached to the sand-bag by straps d, is carried over the pulley e, pivoted at the extremity of the crane-arm, and around the axial pulley a to a fixed pulley, e, upon the wall or ceiling, from whence 45 it is led to a treadle, I, under the work-bench D.

The crane consists merely of a swinging arm pivoted by an axle, f, to a fixed support, as to the ceiling C, or to a bracket, G, secured

to the wall and projected therefrom to a point 50 over the joining-line between the bench D and hot-table E.

The location of the crane, axle, or pivot at this point L allows the crane to be swung with the least resistance toward either bench 55 or table, and the operator can thus move the bag by the attached handles i in the curved path indicated at Z in Fig. 2 with the utmost facility when the weight is lifted by the treadle through the medium of the cord b. 60

In Fig. 1 the sand-bag is shown resting upon the flange F, and the foot-plate of the treadle I elevated to receive the foot of the operator.

In Fig. 2 a section of the wall A is shown 65 and sufficient of the work-bench to show three of the cranes mounted closely together. In this view the function of the pulley a is plainly shown, as when the sand-bag rests upon the hat-flange the cord runs nearly straight over 70 it, but is looped quite around it when the bag is pushed back to rest upon the hot-table for reheating.

With the use of the bent treadle (shown in Fig. 1) another pulley, g, is required to lead 75 the rope to it; but the arrangement of the treadle and cord may be varied in any way to secure the desired result—viz., to raise the weight of the bag by the foot, leaving the hands at liberty to operate the flange and 80 move the bag as required.

By the use of my apparatus all framing for the mechanism is saved, and the indispensable work-bench and hot-table are reduced to the cheapest form by making them continuous. 85

The simplicity of the mechanism, and the attachment of it all to the building employed, enables a great number of sand-bags to be operated in a small space, and their contiguity to one another enables one workman to 90 make use of several bags by preparing the hat and fitting it to one flange while another flange and hat are receiving the required pressure.

Having thus shown how my invention relates largely to the building in which the sand-bag is operated, I desire to claim the crane in combination with such building, and also in

dependently of such voluntary connection, that I may use the same upon suitable framing when preferred.

I claim—

- 5 1. In combination with a hot-table and hat-flange provided with a suitable support near the table, a sand-bag provided with a cord and treadle for raising the weight when desired, and a crane for transferring the sand-bag from the hot-table to the flange, and vice versa, as herein shown and described.
- 10 2. The improved device for transferring

sand-bags to and fro as required, consisting in mounting a series of cranes upon the ceiling or wall of a building, and using the sand-bags 15 upon continuous benches and hot-tables beneath the cranes, as herein set forth.

In testimony that I claim the foregoing I have hereto set my hand, this 17th day of March, in the presence of two witnesses.

ROBERT CLARK, JR.
